UNITED STATES PATENT OFFICE

WARREN S. SILLCOCKS, OF MONMOUTH BEACH, NEW JERSEY, ASSIGNOR, BY MESNE ASSIGNMENTS, TO LUSTEROID CONTAINER COMPANY, INC., OF MAPLEWOOD, NEW JERSEY, A CORPORATION OF NEW JERSEY

CLOSURE FOR COLLAPSIBLE TUBES

Application filed January 24, 1931. Serial No. 510,857.

This invention relates to an improved closure for collapsible tubes and while it is adapted for use on collapsible tubes of metal it is particularly adapted for use on collapsible tubes made of celluloid.

The celluloid tubes are more apt to crack under bending or indentation caused by the known forms of clip. Clips are placed on the flattened ends of the tubes and then either compressed tightly or folded over and then compressed. This latter is the form employed in this invention. The folds are made closely to prevent leakage but the clip does not crack or break the celluloid and presents a positive closure without excessive thickness. Furthermore, when the tube is folded over as is sometimes done to eject material the rounded edge of the fold in engagement with the body of the celluloid tube does not crack or break the material of the tube.

The invention is illustrated in the accompanying drawing in which Figure 1 is a perspective view of a collapsible tube and a clip about to be assembled. Figure 2 is an enlarged section of the end of the tube and the clip after they are assembled and folded and the closure is complete.

The collapsible tube 10 is of the usual form and the wide end 11 is pressed together usually between the thumb and forefinger, for insertion into the clip 12. The clip is made of soft sheet metal, usually tin, and is folded over to form a return bend 13 and two substantially parallel walls 14 and 15. The wall 15 is about half as high as the wall 14 and the return bend 13 is wide enough to receive the end 11 within the bend. When the parts are so assembled the clip with the end 11 is folded over to place the wall 15 inside the wall 14. This brings the return bend opposite the top edge of the wall 14 and presents a rounded surface to the outside of the tube.

In case the clip is turned over to eject material this rounded face engages the celluloid or other material of which the tube is made and does not crack or puncture it.

In the bending or folding of the clip the wall 14 is folded over which forms a trough

55 It will also be noted that in the folding of the material of the tube while tightly rolled or folded engages substantially rounded surfaces and also provides enough fold to make a leak-proof closure.

I claim:—

60 A collapsible tube of celluloid with its flat end having the opposed walls in contact and a clip having one wall approximately twice the height of the other and separated by a space to receive and contact 65 with the contacted walls of the tube whereby a single fold of the clip embeds the edge of the higher wall into the bottom of the U-shaped bend of the tube and presents a rounded top surface for rolling on the tube 70 to prevent laterally cracking of the celluloid and allow the natural resiliency of the material to function.

75 In testimony whereof he affixes his signature.

WARREN S. SILLCOCKS.
